MACHINE FOR WINDING FLAT
OBLONG COILS

Willard C. Shaw, Anderson, Ind., assignor to General Motors Corporation, Detroit, Mich., a corporation of Delaware

Application September 6, 1947, Serial No. 772,560

4 Claims. (Cl. 153—64)

1

This invention relates to the manufacture of electrical forms and its object is to provide a machine for winding relatively heavy wire into a single flat layer. In general, this object is accomplished by a rotatable form against which the wire is pressed by a roller while the form rotates. There are four hydraulically operated devices respectively for clamping the start end of the wire on the form, for urging the wire-engaging roller against the wire under yielding pressure during winding, for rotating the form and for ejecting the wound coil from the form after the clamping device has been released.

Further objects and advantages of the present invention will be apparent from the following description, reference being had to the accompanying drawings, wherein a preferred embodiment of the present invention is clearly shown.

In the drawings:

Fig. 1 is a side view of the machine and in part a diagram of the hydraulic circuits.

Fig. 2 is a plan view.

Fig. 3 is a fragment of the plan view drawn to a larger scale and showing details of the wire-engaging roller and cooperating mechanism.

Fig. 4 is a sectional view on line 4—4 of Fig. 3.

Fig. 5 is a fragmentary, sectional view on line 5—5 of Fig. 2 and is drawn to a larger scale.

Fig. 6 is a longitudinal, sectional view of parts of Fig. 5 which are there shown in side elevation.

Fig. 7 is a sectional view on line 7—7 of Fig. 8.

Fig. 8 is a sectional view on line 8—8 of Fig. 7.

Fig. 9 is a sectional view on line 9—9 of Fig. 1.

Figs. 10, 11 and 12 are diagrammatic views showing the mode of operation of the machine.

Referring to Fig. 1, the frame work of the machine comprises legs 20 and 21 which support side plates 22. Plates 22 support table plates 23 and 24. Legs 21 support a table plate 25 having extension plates 26 and 27 fastened thereto and supported by braces 28 and 29, respectively.

Plate 23 supports a winding cylinder 30 whose piston, not shown, is connected with a rod 31 connected by a bar 32 with a rack bar 34 which is shown in Fig. 8 as being slidable against a flat bearing plate 35 retained by a frame 36 attached by screws 37 to the bottom of table plate 24. The rack 34 is supported upon the frame 36 and also upon a plate 38 located below a bar 39, bars 38 and 39 being attached to the table by screws 40. The rack 34 slides also in contact with a bar 41 which screws 42 attach to table 24.

Referring to Fig. 7, table 24 is welded to a tube 45 carrying bearings 46 within which a shaft 47 is journaled. The upper bearing is retained in the

2

tube by a flange 48 of the shaft bearing against a washer 49 which rests on an annular shoulder provided by the tube. Shaft 47 is connected by a key 50 with gears 51 and 52 which mesh respectively with the rack 34 and a gear 53 which, as shown in Fig. 5, is connected by a key 54 with a tubular shaft 55. Near its lower end shaft 55 is journaled in a bearing 56 retained by a tubular member 57 welded to the table 24. Member 57 supports a step roller bearing 58, the inner race of which is engaged by a shoulder 59 of the shaft 55. Bearing 58 is closed by a tubular cover 60 attached to the shaft 55 by screws 61. A bearing washer 62 is located between the lower end of the members 56 and 57 and the gear 53. Screws 63, threaded into the hub of the gear 53, tighten the connection between the gear 53 and the shaft 55. Gear 53 is supported vertically by plate 64 which screws 65 attach to the lower end of the shaft 55.

The upper end of shaft 55 is connected by screws 70 (see Fig. 6) with the winding form 71 having a plane surface 72 and an oblong boss 73 on which the coil is wound. The boss 73 is provided, as shown in Fig. 8, with surfaces 74 and 75 against which the start end of the coil is clamped before the winding starts. This start end is secured in position by a plate 80 having a downwardly projecting boss 81 which engages the start end of the coil marked C₁ (see Fig. 11). The plate 80 is secured to a rod 82 which extends within the shaft 55 and is provided at its lower end with a clevis 83 connected by pin 84 with the upper end of a rod 85 extending through the shaft 55 and connected at its lower end with a bearing retainer 86 which is threaded on the rod and is secured in adjusted position by lock nuts 87 and 88. A spring 89 urges the rods 85 and 82 downwardly into clamping position. The retainer 86 holds a step bearing 90 held in place by a ring 91 secured by screws 92 to the retainer 86. The lower race of bearing 90 is adapted to receive the upper end of a piston rod 93 (see Fig. 1) attached to a piston within a cylinder 96 supported by plate 97 having holes which receive screws 98 on the ends of rod 99 attached to table 24 in Fig. 1. The plate 97 is located between pairs of nuts 100 threaded on rod 98. The vertical position of the cylinder 96 and of the upper end of rod 95 is determined by adjusting the nuts 100 on the screws 98. When the piston in cylinder 96 rises, rod 95 engages the bearing 90 to move the rods 85 and 82 and the clamping plate 80 upwardly. As the plate 80 rises, it moves toward the right (Fig. 1) due to the action of a leaf spring 101 attached by

a rivet 102 to the rod 82, thereby moving the plate 80 toward the right so that the wound coil can be removed. When the rods 82 move down, the plate 80 moves down and toward the left. It moves toward the left due to the camming action between a stud 103 attached to the plate 80 and engaging an inclined surface 104 of the form 71.

The side bars 22 (Fig. 1) support a cross bar 110 which supports a cylinder 111, whose piston (not shown) is connected with a rod 112 connected by a link 113 with a lever 114 pivoted at 115 on a bracket 116 attached to a plate 117. Plate 117 together with spacers 118 are attached by screws 119 to the upper table 25. Plate 117 is integral with a sleeve 120 supporting a bearing 121 for the upper portion of shaft 55. The shaft 55 is surrounded by a ring 122 which is engaged by the right end of lever 114. When piston rod 112 moves down, lever 114 moves counterclockwise and lifts the ring 122 (Fig. 6) and causes pins 123 resting thereon to move upwardly a stripper plate 124. Plate 124 has its upper surface normally flush with the surface 72 of the form 71. A coil wound on the form extends over the upper surface of the plate 124. Therefore when plate 124 moves upwardly the wound coil is stripped from the form boss 73. When piston rod 112 moves up springs 125 operate to move the stripper 124 to normal position, thereby pressing down on pins 123 which press down on ring 122, thereby returning the parts to normal position.

Referring to Figs. 3, 4 and 5, the upper table 25 supports a plate 130 which is integral with a rod 131 providing a pivot for an arm or triangular plate 132 whose hub 133 has a bearing 134 on the rod 131. The hub 133 is located between ring bearing 135 and end of extension 140, and is retained by washer 137 engaged by nut 138 threaded on the upper end of rod 131. Arm 132, which is of general triangular formation as shown in Fig. 3, carries said extension 140 attached by screws 141 and the arm 132 together with its extension 140 are attached by pins 142 to a sleeve 143 which surrounds a piston rod 144 attached to a piston within a cylinder 145 pivoted at 145a. The sleeve 143 is urged right by a spring 146 confined under compression between the sleeve 143 and nuts 147 threaded on the left end of rod 144. As shown in Fig. 2, the spring 146 is operative to urge the lever 132 clockwise so that a roller 150 supported thereby can engage the wire being wound upon the form. Roller 150 rotates on a pin roller bearing 151 journaled on a rod 152 attached to a block 153 which is supported by the arm 132 and which is retained by a plate 154 attached by screws 155 to the arm 132 and by screws 156 to the block 153. Block 153 supports a roller step bearing 157, the lower race of which engages the roller 150. The plate 154 is provided with an arcuate beveled surface 160 engaged by a frustro-conical roller 161 journaled on a pin 162 carried by block 163 attached to the table plate 25. Due to the cooperation between roller 161 and surface 160, upward thrust of the arm 132 during the winding operation is resisted.

Referring to Fig. 1, a motor driven pump 170 has an inlet 171 connected with an oil tank (not shown) and an outlet 172 connected by pipe 173 with a valve 174 controlled by a pedal 175 and controlling the flow of oil through pipe 176 or pipe 177 to cylinder 96 for operating the clamp plate 80. Pipe 172 is connected also by flow control valve 180 with a pipe 181 connected with a manually operated valve 182 for controlling the flow of oil through one or the other of pipes 183 and 184.

connected with the cylinder 30. Pipe 181 is connected also with a manually operated valve 185 which controls the flow of oil through one or the other of pipes 186 and 187 connected with the knock-out or ejection cylinder 111. Pipe 181 is connected through a check valve 190 with a manually operated valve 191 controlling the flow of oil through one or the other of pipes 192 and 193 which is shown in Fig. 2 and are connected with the cylinder 145. The manually operated valves 182, 185 and 191 may be mounted for convenient operation upon a plate 195 (Fig. 3) which is located above the arm 132 and is supported by brackets 196 attached to the table 25.

The table extension 26 supports a roll of paper ribbon 200 which rotates on a pin 201. The ribbon represented by the line R passes between pressure pads 202 and 203 which keep a certain tension on the ribbon. As shown in Fig. 10, the end of the ribbon is located in the angle defined by the surfaces 74 and 75 of the form 71. The material for the coil C is provided by a copper bar B having the coil end Cs (Figs. 6 and 11) preformed. The coil end Cs is placed against the ribbon R which is against the form surface 75. Then the clamp plate 80 is moved from the position shown in Fig. 10 to that shown in Fig. 11 in order to hold the material in position. While these parts are being located, the pressure fluid is applied to the right end of cylinder 145 so as to hold the roller 150 out of engagement with the form. After the parts have been positioned as shown in Fig. 11 then the roller 150, represented by the dot-dash circle 150, is moved against the bar B. Then the pressure fluid is applied to the left end of cylinder 30, thereby causing the rack 34 to move toward the right, thus causing counterclockwise rotation of the form 71 as shown in Figs. 10, 11 and 12 which results in winding the coil into about three turns as shown in Fig. 12.

The number of turns which can be wound on the form is determined by how far the rack 34 moves toward the right end. This movement is determined by a block 205 (see Fig. 1) which is received by an oblong opening 206 (Fig. 9) in the table 24. The block 205 carries cross pins 207 which rest upon the table 24. When the block 205 is positioned as shown, the rack 34 will have the shortest stroke. If it is inverted so that the rack will engage the surface 208 thereof, the rack would have a longer stroke. The rack 34 can have a still longer stroke by removing the block 205 and allowing the rack to stop against a screw 209 threaded through a lug 210 attached to the bottom of the table 24.

During the winding of a coil, the bar B, which is located upon table extension 27, can whip back and forth between the pair of rollers 211 and 212 secured to the top of said extension.

The operating sequence is as follows: After winding a coil, operate valve 191 to cause roller 150 to move away from coil. Depress pedal 175 to cause valve 174 to lift the clamp plate 80. Operate valve 185 to eject the wound coil. Operate valve 185 to retract the ejector. Operate valve 182 to cause left movement of rack 34 and clockwise rotation of form 71 to start position. Place end of ribbon R in angle formed by surfaces 74, 75 of form 71. Place end Cs of wire B against ribbon R against form. Release pedal 175 to cause valve to effect movement of plate 80 into clamping position. Operate valve 191 to cause roller 150 to engage wire B. Operate valve 182 to cause rack 34 to move right to effect coun-

terclockwise rotation of the form 71 to effect winding the wire B upon the form.

While the embodiment of the present invention as herein disclosed, constitutes a preferred form, it is to be understood that other forms might be adopted, all coming within the scope of the claims which follow.

What is claimed is as follows:

1. A machine for winding a flat, oblong coil of wire comprising a winding form having a plane surface and an oblong boss extending therefrom, means for rotating the form, a member rotatable with the form and engageable with the start end of the wire to clamp it against the plane surface of the form, means for yieldably urging the wire toward the oblong boss of the form during winding, means for effecting movement of said member away from the side of the wound coil and also toward the axis of rotation of the form, and means for stripping the coil from the form after the member has been so moved.

2. A machine according to claim 1 in which the means for rotating the form includes a tubular shaft carrying the form and in which the means for moving the wire securing member comprises a rod extending through the shaft, and attached to said member, a spring for urging the rod in the direction for advancing the member toward the wire, a device for moving the rod in the direction to retract the member from the wire, a spring for urging the member in a direction toward the axis of rotation of the form when the member is moved away from the wire, and cam and cam follower elements, one provided by the form and the other by the member and cooperating, as the member is moving toward the form, to cause said member to move away from the axis of rotation of the form.

3. A machine for winding a flat, oblong coil of wire comprising a winding form having a plane surface and an oblong boss extending therefrom, a rotatable shaft carrying the form, a rack,

gearing connecting the rack and the shaft, fluid pressure means for moving the rack in one direction to wind wire upon the form and for moving the rack in the opposite direction to restore the form to its starting position, an adjustable stop for variably limiting movement of the rack in the first mentioned direction in accordance with the amount of wire to be wound upon the form, means rotatable with the form for securing the start end of the wire to the form, and means for yieldably urging the wire toward the oblong boss of the form during winding.

4. A machine for winding a flat, oblong coil of wire comprising a winding form having a plane surface and an oblong boss extending therefrom, means for rotating the form, means for yieldably urging the wire toward the oblong boss of the form during winding, a member rotatable with the form and engageable with the start end of the wire to clamp it against the plane surface of the form, means for effecting movement of said member away from the side of the wound coil and also toward the axis of rotation of the form, a plate rotatable with the form and having a plane surface normally flush with the plane surface of the form, said surfaces being contacted by the wound coil, and means for moving the plate axially to strip the coil from the boss of the form.
